PORTABLE STEREO PHONOGRAPH OR SIMILAR ARTICLE

Albert T. Rayburn, Columbus, and David B. Rote, Fort Wayne, Ind., assignors to Arvin Industries, Inc., Columbus, Ind., a corporation of Indiana

Filed Nov. 6, 1967, Ser. No. 9,274

Term of patent 14 years

(Cl. D56—4)

Fig. 1

Fig. 2

Fig. 3

Fig. 5

Fig. 4

FIG. 1 is a perspective view of a portable stereo phonograph or similar article showing our new design;

FIG. 2 is an end elevation thereof showing the opposite end from that shown in FIG. 1;

FIG. 3 is a top plan view thereof;

FIG. 4 is a rear elevation thereof; and

FIG. 5 is an exploded perspective view thereof similar to FIG. 1, but showing the speakers removed from record player.

The dominant features of the design are shown in full lines.

We claim:

The ornamental design for a portable stereo phonograph or similar article, as shown and described.
